DESIGN FOR A REFRIGERATOR CABINET

Ralph E. Kruck, Springfield, Mass., assignor to
Westinghouse Electric & Manufacturing Com-
pany, a corporation of Pennsylvania

Application April 23, 1935, Serial No. 56,522

Term of patent 7 years

To all whom it may concern:

Be it known that I, Ralph E. Kruck, a citizen
of the United States, residing at Springfield, in
the county of Hampden and State of Massa-
chusetts, have invented a new, original, and
ornamental Design for a Refrigerator Cabinet,
of which the following is a specification, refer-
ence being had to the accompanying drawing,
constituting a part thereof.

The single figure is a perspective view of a
refrigerator cabinet showing my design.

What I claim is:

The ornamental design for a refrigerator cabi-
net substantially as shown.

In testimony whereof, I have hereunto sub-
scribed my name this 15th day of April 1935.

RALPH E. KRUCK.
